Boehleke & Lecketter

UNITED STATES PATENT OFFICE

FRANKLYN H. HULL, OF HAWTHORNE, NEW JERSEY, ASSIGNOR TO AUSTRAL
WINDOW COMPANY, OF NEW YORK, N. Y., A CORPORATION OF MAINE

COMBINED DOOR BUMPER AND COAT HANGER

Application filed November 6, 1928. Serial No. 317,679.

This invention relates to a combined door bumper and coat hanger and has for its principal object the provision of a device of this character which affords the maximum degree 5 of resiliency for the absorption of shock in a construction which is practical from the standpoint of ease and cheapness of manufacture and installation and durability in use.

10 In accordance with the invention, a generally U-shaped member of resilient material is secured to a door at the proper elevation to serve as a coat hanger or the like, and is so positioned on the door as to contact 15 with the wall or other obstruction when the door is opened and absorb the shock and cushion the impact.

This and other objects of the invention and the means for their attainment will be 20 more apparent from the following detailed description, taken in connection with the accompanying drawings, illustrating one modification by which the invention may be realized, and in which:

25 Figure 1 is a view showing, in side elevation and partly in section, the combined door bumper and coat hanger, applied to a door.

Figure 2 is a view showing the device in 30 end elevation, looking from the right in Figure 1.

The combined door bumper and coat hanger may be secured to a door 10 at a convenient height above the floor. Preferably, the coat hanger is formed of a generally U-shaped member 11 having one longer arm or side 12 provided with apertures 13 by which that arm may be secured, as by the screws 14, to the door. The other arm 16 of the coat hanger is conveniently 35 made shorter than the arm 13 and may, if desired, be turned inwardly slightly, as at 17 to provide, what is in effect, a resilient hook upon which a hat may be hung. Obviously, a garment may be hung on the arm 16 or a 40 newspaper suitably folded may be yieldingly held between the arms 13 and 16. It may also be found convenient to secure a hook 20 to the lowermost part of the member 11. Thus, a coat may be suspended from the hook 45 20 and a hat carried by the arm 16. Obvious-

ly, the wall may be the support for the coat hanger instead of the door.

A hanger such as described may be disposed upon the inside of the door, i. e., that side which is adapted to swing inwardly and 55 engage the wall or other enclosure in which the door is mounted. Thus, when the door is opened and swings back against the wall, the bumper, and particularly the shorter arm 16 thereof, strikes against the wall and cushions 60 the blow, maintaining the door spaced from the wall as will be readily understood. If desired, a button 22 of yielding non-metallic material such as rubber may be carried by the shorter arm 16. 65

It will thus be seen that a combined door bumper, coat hanger and newspaper rack is provided, which is extremely simple in its construction, affords the maximum resiliency 70 in the cushioning of blows and is practical from the standpoint of manufacture and installation.

Various modifications will occur to those skilled in the art in the composition and configuration of the component elements going 75 to make up the invention as a whole, and no limitation is intended by the phraseology of the foregoing description or illustrations in the accompanying drawings, except as illustrated in the appended claims. 80

What I claim is:—

1. A combined door bumper and coat hanger comprising a U-shaped member, means to secure one arm of said member to a door, the other arm of said member having 85 cushioning means serving as a door bumper and a hook carried on the said member.

2. A combined door bumper and coat hanger comprising a U-shaped member of resilient material whereof one arm is longer 90 than the other, means to secure the longer arm to a door, a cushion of yielding non-metallic material secured to the other arm and a hook carried with the U-shaped member. 95

In testimony whereof I affix my signature.
FRANKLYN H. HULL.
